US0D1027211S

(12) **United States Design Patent** (10) Patent No.: **US D1,027,211 S**
(45) Date of Patent: ** May 14, 2024

(54) **MASSAGE DEVICE**

(71) Applicant: **Therabody, Inc.**, Los Angeles, CA (US)

(72) Inventors: **Jaime Sanchez Solana**, Los Angeles, CA (US); **Eduardo Merino**, Los Angeles, CA (US); **Zenger Zhou**, Shenzhen (CN); **Lymond Lin**, Shenzhen (CN); **Sunny Wang**, Dongguan (CN); **Tony Zhong**, Shenzhen (CN); **Danny Zeng**, Shenzhen (CN); **William Webb**, San Francisco, CA (US); **Phil Huang**, Shenzhen (CN); **Yano Pang**, Shenzhen (CN)

(73) Assignee: **Therabody, Inc.**, Los Angeles, CA (US)

(**) Term: **15 Years**

(21) Appl. No.: **29/913,136**

(22) Filed: **Sep. 27, 2023**

(51) LOC (14) Cl. **24-01**

(52) U.S. Cl. **D24/215**
